UNITED STATES PATENT OFFICE.

JOSEPH HAYES, OF DOVER, NEW HAMPSHIRE.

NUT-LOCK.

SPECIFICATION forming part of Letters Patent No. 339,172, dated April 6, 1886.

Application filed February 8, 1886. Serial No. 191,120. (No model.)

To all whom it may concern:

Be it known that I, JOSEPH HAYES, of Dover, in the county of Strafford, of the State of New Hampshire, have invented a new and 5 useful Improvement in Nut-Locks; and I do hereby declare the same to be described in the following specification and represented in the accompanying drawings, of which—

Figure 1 is a front elevation; and Fig. 2, a 10 transverse and vertical section of part of a railway-rail and its fish-plates, their connecting-bolt, and a nut-lock thereto, provided with my invention, the nature of which is defined in the claim hereinafter presented.

15 In the drawings, R denotes the rail portion; A, the screw-bolt; B, its nut; C, the nut-lock; and D and E, the fish-plates, the said nut-lock being between the nut and the next adjacent fish-plate.

20 The nut-lock may be of the kind described and claimed in Letters Patent No. 330,237, dated November 10, 1885, and granted to me, or it may be a simple piece of plate metal, rectangular in shape, and bent or doubled 25 upon itself and turned at or near one end up against the edge of the nut, the lower edge resting on the rail, or the flange of the fish-plate and the bolt going through the folded parts, and all being as represented.

30 In carrying out my invention, I combine with such a nut-lock a stuffing or plate, F, of an elastic material, interposed between the lapped parts a b, and filling or nearly filling the space between them, the bolt going directly through such stuffing or plate. The 35 said plate F may be of rawhide, or of "leather board," or some other proper elastic substance, such as when the nut is screwed hard up against the outer lap, b, of the nut-lock, will give way or become so pinched between the laps as to operate as a spring to aid in preventing the nut and bolt from working loose.

40 From the above it will be seen that the elastic plate by being within the nut-lock or between its lapped portions is not only covered and protected thereby from rain or snow and from abrasion or wear, but is securely held from revolving with or being revolved by the 45 nut when the latter is being turned against

the nut-lock. Thus while the elastic plate answers the purpose of a washer to aid in preventing the bolt and nut from working loose, it becomes protected by the nut-lock not only as mentioned but from being injured by the 55 nut.

I am aware of the compound washer described in United States Patent No. 329,615, and consisting of an annulus of elastic material and an envelope of plate metal consisting 60 of two flat annuli connected by a neck having a width less than either of them. I am also aware of the washer described in the United States Patent No. 132,807, and consisting of a wooden annulus and two annular metallic 65 caps between which such annulus is arranged. I am also aware of the rail-splicing safety-lock described in the United States Patent No. 308,810. Neither of the above-referred to devices has like my nut-lock a rectangular 70 plate folded at its middle, and having one end—viz., the inner one—straight and extended down to the base-flange of the rail, and serving therewith to prevent the doubled or folded plate C from turning on the bolt, the 75 plate near its other end being extended below or beyond, and bent up against the edge of the nut in order to prevent the nut from revolving on the bolt.

The elastic plate answers the purpose of a 80 washer to aid in preventing the bolt and rail from working loose.

I claim—

In combination with the screw-bolt and its nut, and with the nut-lock consisting of the 85 rectangular plate C, bent or folded at its middle, and perforated, as described, to receive the bolt, the elastic plate F, fitting the space between the laps of the plate, and also perforated to receive the bolt, the whole being so 90 that when the plates C and F are used on a screw-bolt going through a rail and its fish-plates one lap of the plate C shall extend down to or closely to the base of the rail and the other lap be bent against the edge of the 95 nut, as represented.

JOSEPH HAYES.
